INVENTOR.
John L. Beck
BY
Thomas W. Y. Clark
ATTORNEY.

UNITED STATES PATENT OFFICE.

JOHN L. BECK, OF BALTIMORE, MARYLAND.

SIGN.

Application filed March 17, 1927. Serial No. 175,969.

My invention relates to a sign that a blind person might carry in his pocket usually, but, when crossing streets it would be exhibited. Recently a blind man stood on a 5 car track in Baltimore, waving his hands for some one to help in directing him. A motorman thought he was simply trying to make the car stop at a non-stop corner, and therefore, did not stop his car and killed 10 the man.

The objects of my invention are to make a sign that is readily visible when displayed, and one which will tell that the user is handicapped by not being able to see, to 15 make one which will not injure a person standing near should he be unintentionally struck with it, to make one which the user can tell by his sense of feeling has the inscription right side up, to make one that can 20 be firmly held, to make one that can be put in his pocket or a lady's hand bag except when needed at a crossing, and other objects and advantages will appear as the description proceeds and from the accompanying drawing forming a part hereof and in 25 which,

Figure 1 is a front elevation of a sign embodying my invention. Figure 2 is an end view thereof. Figure 3 is a view of a similar sign for night use. Figure 4 is a view 30 on line 4-4 of Figure 3 looking in the direction of the arrows. Figure 5 is a view on line 5-5 of Figure 3 looking in the direction of the arrows.

Similar numerals refer to similar parts 35 throughout the several views.

The sign 1, is colored orange or a tone thereof which is thought to be the color most easily seen and least confused with 40 other objects in ordinary use. The inscriptions are on both sides, exactly alike and are upright from the same edge of the sign. A hole or opening 2 is at one end, nearer 45 one edge, preferably, the lower, than the other. This makes it possible for the user to keep the inscriptions upright and makes the sign easily grasped, a little like a pistol. The sign is preferably made of laminated sections, 3-4-3, to prevent warping.

Should it be desirable to use a sign at 50 night, I have shown in Figures 3-5 inclusive a modification of the sign shown in Figures 1 and 2, in which the sign 9 is made of thin sheet material, such as metal, and it is also colored orange, but in the drawing this coloring is omitted to let the other parts stand out more clearly. The word "Blind" is cut out on each side, and the other inscriptions, not needing to be seen so clearly, are painted on the sign. Inside the sign is a long electric bulb, shown at 6, connected by wires to a small battery 7 and the holding opening 2 has a plug switch 8 to close the circuit between the battery and light. 60

It is designed to have the users of these 65 signs licensed by the police department and to prevent their use by police regulation except by those having a license.

The signs are as much, or more, to protect 70 the driving public than the blind, for no one knowingly would run down a blind person. Also the sign must be small because a blind person does not want to advertise his handicap except when it is essential for his safety 75 and the safety of the public.

It is understood that various modifications 80 may be made in the general design and structural details of the device as herein disclosed without, however, departing from the spirit or scope of my invention as defined in the following claims.

I claim:

1. A pocket size sign oblong and substantially rectangular, with an opening therethrough adjacent one end and nearer 85 one long edge thereof than the other for the insertion of the user's finger, and whereby the upright position of said sign may be determined by the sense of touch.

2. A pocket size elongated sign with an 90 opening therethrough adjacent one end and nearer one long edge thereof than the other for the insertion of the user's finger, and whereby the upright position of said sign 95 may be determined by the sense of touch.

JOHN L. BECK.
